United States Patent Office

Des. 220,822
Patented May 25, 1971

220,822

JACKET

Thomas E. De Wan, 9600 N. Lake Drive,
Milwaukee, Wis. 53217

Filed Oct. 6, 1969, Ser. No. 19,439

Term of patent 14 years

Int. Cl. D2—01

U.S. Cl. D2—189

FIG. I.

FIG.2.

FIG. 1 is a front perspective view of a jacket showing my new design, the side opposite being a mirror image thereof; and

FIG. 2 is a rear perspective view thereof.

I claim:

The ornamental design for a jacket, as shown and described.
